CLAIM

The ornamental design for a multi-stone ring, as shown and described.

DESCRIPTION

FIG. 1 is a front elevational view of a multi-stone ring

showing my new design;

FIG. 2 is a top plan view;

FIG. 3 is a side elevational view;

FIG. 4 is a front elevational view of a multi-stone ring showing a second embodiment of my new design;

FIG. 5 is a top plan view of FIG. 4;

FIG. 6 is a side elevational view of FIG. 4;

FIG. 7 is a front elevational view of a multi-stone ring showing a third embodiment of my new design;

FIG. 8 is a top plan view of FIG. 7;

FIG. 9 is a side elevational view of FIG. 7;

FIG. 10 is a front elevational view of a multi-stone ring showing a fourth embodiment of my new design;

FIG. 11 is a top plan view of FIG. 10;

FIG. 12 is a side elevational view of FIG. 10;

FIG. 13 is a front elevational view of a multi-stone ring showing a fifth embodiment of my new design;

FIG. 14 is a top plan view of FIG. 13; and,

FIG. 15 is a side elevational view of FIG. 13.
